Primary Examiner — Garth Rademaker*Assistant Examiner* — Katelin G Kloberg(74) *Attorney, Agent, or Firm* — James F. Lee, III; Gable Gotwals(57) **CLAIM**

The ornamental design for a spinning reel, as shown and described.

DESCRIPTION

FIG. 1 is a perspective view of a spinning reel, showing my design;
 FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The dash-dot-dash broken lines depict boundaries of the claim and form no part of the claimed design. The evenly-spaced broken lines depict portions of of a spinning reel that form no part of the claimed design.

1 Claim, 7 Drawing Sheets(56)
